[57] CLAIM

The ornamental design for a nozzle for plasma arc torch, as shown and described.

DESCRIPTION

FIG. 1 is a perspective view of a first embodiment of a nozzle for plasma arc torch showing my new design;
FIG. 2 is a typical side elevational view of the nozzle for plasma arch torch of FIG. 1;
FIG. 3 is a top plan view of the nozzle for plasma arc torch of FIG. 1;
FIG. 4 is a bottom plan view of the nozzle for plasma arc torch of FIG. 1;
FIG. 5 is a perspective view of a second embodiment of a nozzle for plasma arc torch showing my new design;
FIG. 6 is a typical side elevational view of the nozzle for plasma arc torch of FIG. 5;
FIG. 7 is a top plan view of the nozzle for plasma arc torch of FIG. 5;
FIG. 8 is a bottom plan view of the nozzle for plasma arc torch of FIG. 5;
FIG. 9 is a perspective view of a third embodiment of a nozzle for plasma arc torch showing my new design;
FIG. 10 is a typical side elevational view of the nozzle for plasma arc torch of FIG. 9;
FIG. 11 is a top plan view of the nozzle for plasma arc torch of FIG. 9; and,
FIG. 12 is a bottom plan view of the nozzle for plasma arc torch of FIG. 9.
